UNITED STATES PATENT OFFICE.

LEONARD D. MORRIS, OF CHICAGO, ILLINOIS.

CHIME-STRIKING ACTION.

1,415,256.

Specification of Letters Patent. Patented May 9, 1922.

Application filed August 7, 1919. Serial No. 315,801.

To all whom it may concern:

Be it known that I, LEONARD D. MORRIS, a citizen of the United States, residing at Chicago, in the county of Cook and State of Illinois, have invented certain new and useful Improvements in Chime-Striking Actions, of which the following is a specification.

My invention relates to chime striking actions and has for its primary object the provision of an improved device for mechanically sounding resonant objects, such as chimes, bells and the like, and to produce a strong and unobstructed vibration of the same. A further object is to provide an action by which such vibration may be damped. Another object lies in the provision of a novel form of electrically operated action whereby a hammer driven against the chime, is instantly and positively withdrawn therefrom, to leave the chime free to vibrate.

Other objects and advantages of the invention will appear from the following description, taken in conjunction with the accompanying drawings which form a part of this specification and illustrate the preferred embodiment of the invention.

In the drawings:

Fig. 1 is a side elevation of the invention, certain stationary frame members being shown in section.

Fig. 2 is a similar view illustrating in full and dotted lines respectively, two different positions of the parts.

Fig. 3 is a section on line 3—3 of Fig. 2.

Fig. 4 is a fragmentary front elevation of a set of chimes, illustrating two positions of the chime damper of the present invention.

The main support for this invention comprises a lower frame member 10, an upper front member 11, and an upper rear member 12, as well as a bar 13 intermediate these upper and lower members and against which the hammer lever rests.

The chimes 14, 15 and 16 are suspended by a cord 17 which passes over buttons 18 carried by a plate 19, the latter being screwed to the front frame member 11. This form of chime mounting is not claimed herein, as it forms the subject-matter of my co-pending application Serial No. 315,802, filed August 7, 1919. While tubular chimes are herein illustrated and described as the sound producing elements to be vibrated by this invention, it is to be understood as being with-

in the purview of the invention that many other resonant objects adapted for vibration by a hammer may be substituted therefor.

The invention contemplates a separate action for sounding and damping each chime. Secured to and projecting from the rear face of the lower frame member 10, is a bracket 21 from which depends an electromagnet generally indicated at 22 and having the axes of its two core ends vertically positioned, the cores of magnets 22 being indicated at 23. The axes of the cores 23 define a vertical plane indicated by the line 24 in Figures 1 and 2. Hinged as at 25 to bracket 21, is a pivot plate 26, carrying an oppositely extending pivot pin 27 soldered or otherwise secured to said plate and having its outer end adjustably spaced from the free end of bracket 21 by means of a spacing screw 28 and a lock nut 29 carried thereby. An armature 31 is secured in the lower end of an armature yoke 32, the sides 30 of which are respectively pivoted on the pivot pin 27 and extend upwardly therefrom and are inclined toward each other to carry a hammer arm 33 which is rigidly secured to them by rivets 34. The pivot pin 27 has its axis positioned horizontally in the plane indicated at 26 and above the cores 23 of the magnet. The armature 31 is thus mounted to swing across the lower ends of the cores 23. By means of screws 35 a metal hammer rod 36 is attached to the wooden hammer arm 33 and, at its upper end, carries a hammer 37 employed in sounding the chime 15 for example. In the position of rest of the hammer and armature the upper end of the hammer arm lies against the felt surface 38 of a cushioned stop 39 mounted by means of a screw 41 upon the bar 13. For producing the best sounds from the chime the hammer 37 is so positioned as to strike the chime at its upper end and above the level at which cord 17 passes through the chime. A post 42 extends upwardly from the upper rear frame member 12 and carries a pivot 43 upon which is mounted the rear end of a damper arm 44. The forward end of the damper arm is formed with a downwardly flaring aperture 45 through which passes a damper rod 46, the upper end of the latter being threaded for reception of upper and lower retaining nuts 47 and 48 by means of which the damper rod is adjustably retained in position in the damper arm and at the same time is allowed a slight amount of angular

play with respect to the damper arm. Preferably the damper rod 46 passes through a guide bearing 49 comprising a horizontally outbent flange formed on the plate 19. The 5 damper rod carries on its lower end a damper 51 of any suitable form by means of which the hammer induced vibration of the chime is damped. A link 52 forms the operating connection between the upper end of hammer arm 33 and the medial portion of damper arm 44, the link being pivoted on horizontal axes in each of these members.

In the position of rest of the action, shown 15 in Fig. 1, the hammer mounting, comprising yoke 30, hammer arm 33, hammer rod 36, and the armature 31, is obliquely positioned so that its upper portion above pivots 27 stands rearwardly of the vertical plane 24 while its lower portion, including armature 20 31, stands forwardly of the lower ends of the magnet cores 23. Upon energization of 25 the electro-magnet, the cores 23 exert a sudden and violent pull on armature 31 thereby drawing the armature backward and swinging the hammer and its whole mounting in a counter-clockwise direction as the parts are viewed in Figs. 1 and 2. The axis of the hammer mounting is indicated by a line 53 in Fig. 1. The sudden magnetically induced 30 rearward movement of armature 31 sets up sufficient momentum in the whole hammer mounting and the hammer to cause the armature to swing across the cores 23 and, even across the lines of magnetic force, to 35 carry the hammer and mounting to the oppositely inclined dotted line position of Fig. 2, in which position the hammer strikes chime 15. The continued energization of 40 the magnet however draws the armature from the rear end of its path of movement as indicated in dotted lines in Fig. 2 to a position directly below and centrally of the magnet cores 23, thereby withdrawing hammer 37 instantly from contact with the 45 chime and holding it firmly in spaced relation to the chime as indicated in full lines in Fig. 2. In this latter position of the parts the axis 53 of the hammer mounting coincides with the plane 24 defined by the axes 50 of cores 23.

The above described initial counter-clockwise movement of the hammer mounting throws the upper end of the hammer forward and upward thereby conveying an upward thrust through link 52 to the damper arm 44, with the result of elevating the damper 51 to a position spaced above the upper end of the chime as shown in Fig. 2. So long as the magnet is energized therefore 55 the chime is free to vibrate under the single initial blow of the hammer, inasmuch as the hammer and damper are both held spaced from the chime. By means of a light 60 spring 54 compressed between the lower frame member 10 and the upper portion of 65

the hammer mounting, the hammer and its mounting are returned to the position of rest of Fig. 1 upon de-energization of the magnet. As the hammer returns to this position the damper 51 is lowered upon the upper end of the chime thus arresting the vibration of the latter. Obviously, the force with which the hammer 37 is projected against the chime may be varied by adjustment of the pivot plate 26 to bring armature 31, during its arcuate movement, closer to the cores 23 or to position it farther from them. Should it be desired to employ a magnet relatively extremely powerful with respect to the weight of hammer and hammer mounting which it is to actuate, I contemplate the use of spring steel in hammer rod 36 so that, if the power of the magnet is so great as to prevent the momentum of the parts from swinging armature 31 rearwardly of a central position below cores 23, the forward momentum of the hammer 37 will bend the resilient spring arm 36 causing it to travel forward to the dotted line position of Fig. 2 and strike the chime while the remainder of the hammer mounting occupies rigidly the vertical position shown in full lines in Fig. 2.

I claim:

1. In a chime striking action, the combination with a suitable frame, of a chime vertically suspended therefrom, an electro-magnet carried by the frame with the axis of its core parallel with that of the chime, a substantially straight hammer mounting pivoted by its medial portion on a horizontal axis near the upper end of the magnet core, a hammer carried on the upper end of said mounting, an armature fixed on the lower end thereof, a stationary cushion stop limiting movement of the hammer from the chime, and a spring normally holding said mounting against the cushion stop.

2. In a chime striking action, the combination of a vertically disposed electro-magnet, a yoke pivoted above said magnet and provided at its lower end with an armature adapted to be actuated by said magnet, a hammer carried by said yoke above the magnet, a chime disposed in the path of movement of said hammer, a horizontally disposed arm pivotally mounted above said hammer, a damper suspended from said arm in alignment with said chime, a link pivotally connecting said arm and said hammer support providing in conjunction with said support a toggle adapted upon movement of said hammer toward said chime to lift said arm whereby said damper is lifted out of engagement with said chime, and means for restoring said hammer to inoperative position and re-engaging said damper with said chime.

3. In a chime striking action, the combination of a chime, an arm pivoted above said

chime, a damper suspended from said arm in position to engage said chime, toggle mechanism for actuating said arm comprising a pivotally mounted hammer support and a link pivoted thereto and to said arm, a hammer carried by said support, means for swinging said support so as to straighten said toggle and thereby lift said damper from said chime, and means acting on said 10 toggle mechanism to restore said hammer to inoperative position and positively depress said damper into engagement with said chime.

4. In a chime striking action, the combination of a chime, a pivotally mounted arm, a damper adjustably suspended from the free end of said arm in vertical alignment with said chime, a hammer support pivoted upon a horizontal axis, a hammer carried thereby, means for swinging said support across a vertical plane passing through the pivot of said support, a positive toggle link 20

connection between said arm and said support for lifting said damper carrying arm upon striking movement of said hammer, 25 and a spring acting on said hammer support to depress said damper into engagement with said chime.

5. In a chime striking action, the combination of a chime, a hammer therefor, a support for said hammer mounted to oscillate upon a horizontal axis, means for normally maintaining said support in an inclined position with respect to a vertical plane through said axis, a damper carrying arm fulcrumed 35 at one end, a damper adjustably carried by the free end of said arm, and a link connection between said arm and said hammer support for positively lifting said damper upon movement of said hammer toward the chime 40 and for positively depressing said damper into engagement with the chime upon movement of the hammer away from said chime.

LEONARD D. MORRIS.
